ARCH CONSTRUCTION

Hugo A. F. Abt, Elmhurst, Ill.

Application December 24, 1930, Serial No. 504,574

4 Claims. (Cl. 108—23)

This invention relates to arches and more particularly to an arch structure formed from standard rolled metal H or I-beams and adapted for any use where an open space is required, especially where the inside appearance and headroom are important, as for instance, in garages, hangars, green-houses, manufacturing plants, bath-houses, shelters, pavilions, auditoriums, dance halls, etc.

10 Standard arches for building construction with their numerous advantages such as graceful appearances, unobstructed headroom, less weight for the same strength, etc., would supplant the ordinary trusses in many cases if the fabricating costs were not excessive. The beam arch of this 15 invention solves this problem by eliminating expensive lattice work and trussed and curved sections so as to provide a structure comparable in cost to an ordinary truss.

20 In the drawings:

Figure 1 is a sectional view through a building, having its roof supported by arches constructed in accordance with this invention.

25 Figure 2 is a similar view showing a slightly modified form of arch.

Figure 3 is an elevation on a larger scale of one of the column members of the arch.

Figure 4 is an elevation of one of the beam members of the arch of Figure 1.

30 Figure 5 is a similar view of one of the beam members of the arch of Figure 2.

Referring more particularly to the drawings, the arches are composed of column members A and beam members B extending upwardly and 35 inwardly toward each other from the opposite columns to a meeting point midway between said columns.

The columns A and beams B are all formed from standard rolled H or I-shaped sections and 40 are connected or joined in any suitable manner, such as riveting, bolting, or welding.

45 Preferably the columns and beams will be made of H-sections although the ordinary structural shapes known as I-beams also may be employed.

45 The columns A have their webs slit longitudinally from their upper ends downwardly for an appreciable distance, as at 2, and have their inner flanges and the inner portion of their web paralleling the slit 2 bent inwardly forming 50 a section 3 of a knee C.

55 The beam members B of the arch have their webs slit longitudinally from their outer ends which abut the columns A inwardly for an appreciable distance, as at 4, and have their inner flanges and the inner portion of their web par-

alleling the slit 4 bent inwardly forming a second section 5 of the knee C.

The abutting ends of the columns A and beams B are secured together by splice-plates 6 either by welding as shown at the right-hand side of Figure 1 or by riveting as shown at the left-hand side of the figure, and the knee sections 3 and 5 are similarly secured together by splice-plates 7. The slitting and bending of the columns and beams A and B, as above described, provide the necessary section to take care of the moment at this point.

The beams B are joined at their meeting point by splice-plates 8 either welded as shown at the right-hand side of the joint or riveted as shown at the left-hand side of the joint.

The knee portion of the arch may be and preferably is further reenforced and stiffened by a strut 9.

It will be understood that when desired the struts 9 may be omitted and a plate or plates may be used covering the opening caused by slitting the webs of the arch members. The plates may be either riveted or welded in position and may be stiffened in any usual manner, as desired. 80

The thrust of the arch may be resisted in the usual manner by the footings 10 or a tie 12 may be provided connecting the column bases and hidden below the floor.

In the arch construction of Figure 2 the ridge or apex portion of the arch is slit to provide increased section. The remainder of this arch is of the same construction as that described above, therefore the same reference numerals are applied thereto.

90 In this modified form of arch the abutting ends of the beams B have their webs slit longitudinally from their abutting ends inwardly for an appreciable distance, as at 13, and have their inner flanges and the inner portion of their web paralleling the slit 13 bent inwardly forming a knee section 14. The beams B of this construction have their ends and the ends of the knee sections 14 joined by a splice or cover plate 16 which may be either welded or riveted to the beams.

100 The slits in the webs of the members making up the arch may be made by any suitable means such as flame cutting or shearing, and the knee sections may be bent either hot or cold in forming presses or by bending rolls, as desired.

105 By the use of suitable bending apparatus and standardizing the arch members the cost of beam arches such as described herein may be reduced considerably below that of ordinary trusses. As an example of standard arches, arches from 110

forty to one hundred feet in width will have the same radii for the bent portions, and arches from one hundred to two hundred feet will have a second radii. Buildings can thus be standardized, varying only the depths and weights of the beam sections.

The beam arch of this invention takes the place of a truss, knee braces and column supports. The comparatively few members of two rafters or 10 beams, two column supports, and a horizontal tie member perform the same structural duties and replace a truss with its many members, two knee braces, and two columns. This beam arch has less weight and is more economical to fabricate than the truss construction. The beam arch presents a better appearance and adapts itself admirably to the architecture and decorative scheme of a hall or auditorium and greater headroom is obtained than possible with trusses 15 due to the elimination of the bottom chord and web systems of truss construction.

The beam arch may be more readily erected due to the fact that there are fewer parts and consequently fewer joints to be made in the field. 20 The construction of the beam truss also lends itself to welding due to the small number and simplicity of the joints.

Many other advantages resulting from the use 25 of the beam arch of this invention will be readily apparent to those skilled in the art and it will be readily appreciated that this structure may be used wherever an arch is desirable.

While I have shown and described certain specific embodiments of my invention I do not wish 30 to be limited thereto since various modifications may be made without departing from the scope of my invention, as defined in the appended claims.

I claim:

40. 1. An arch supporting structure composed of standard rolled H-sections, said structure comprising one-piece column members at each end and one-piece beam members extending between and connecting said columns, said beam members being inclined upwardly from each column and joined midway between said columns, said columns and said beam members having their webs slit longitudinally from their abutting ends for a material distance and having the inner portions 45 of their web and inner flanges bent inwardly to provide the necessary section to take care of the moment adjacent the point of juncture of the columns and beams, and means cooperating with the columns for resisting the thrust of the arch.
50. 2. An arch supporting structure comprising

single one-piece rolled H-shaped column members at each end and one-piece rolled H-shaped beam members extending between and connecting said columns, said beam members being inclined upwardly from each column and joined midway between said columns, said columns and said beam members having their webs slit longitudinally from their abutting ends for a material distance and having the inner portions of their web and inner flanges bent inwardly to form a knee portion and provide the necessary section to take care of the moment adjacent the point of juncture of the columns and beams, and said beams also having webs slit longitudinally from their abutting ends for a material distance and having the inner portion of their web and inner flanges paralleling said last named slit bent inwardly to provide the necessary section to take care of the moment adjacent the point of juncture of said beams.

3. An arch supporting structure comprising single one-piece rolled flanged structural column members at each end and one-piece rolled flanged structural beam members extending between and connecting said columns, said beam members being inclined upwardly from each column and joined midway between said columns, said columns and said beam members having their webs slit longitudinally from their abutting ends for a material distance and having the inner portions of their web and inner flanges bent inwardly to form a knee portion and provide the necessary section to take care of the moment adjacent the point of juncture of the columns and beams, and said beams also having webs slit longitudinally from their abutting ends for a material distance and having the inner portion of their web and inner flanges paralleling said last named slit bent inwardly to provide the necessary section to take care of the moment adjacent the point of juncture of said beams.

4. A supporting structure composed of a standard rolled H-section, such structure comprising one-piece column members at each end and one-piece beam members extending between and connecting said columns, said column and said beam members having their webs split longitudinally from their abutting ends for a material distance and having the inner portions of their web and inner flanges bent inwardly to provide the necessary section to take care of the moment adjacent the point of juncture of the columns and beams, and anchoring means for said columns.
